US00D753190S

(12) **United States Design Patent**
Geier et al.

(10) **Patent No.:** US D753,190 S
(45) **Date of Patent:** ** Apr. 5, 2016

(54) **COMPACTION MACHINE**

(71) Applicant: **Wacker Neuson Production Americas LLC**, Menomonee Falls, WI (US)

(72) Inventors: **Daniel Geier**, Colgate, WI (US); **David Schulenberg**, Kewaskum, WI (US)

(73) Assignee: **Wacker Neuson Production Americas LLC**, Menomonee Falls, WI (US)

(**) Term: **14 Years**

(21) Appl. No.: **29/509,463**

(22) Filed: **Nov. 18, 2014**

(51) LOC (10) Cl. **15-03**

(52) U.S. Cl. **D15/20**
USPC **D15/20**

(58) **Field of Classification Search**

USPC D15/10, 20, 28, 33, 22
CPC E02D 3/00-3/126
See application file for complete search history.

(57) **CLAIM**

The ornamental design for a compaction machine, as shown and described.

DESCRIPTION

FIG. 1 is an isometric view of a compaction machine incorporating our new design, viewed from above, in front of, and from the left side of the compaction machine;

FIG. 2 is an isometric view of the compaction machine of FIG. 1, viewed from above, in front of, and from the right side of the compaction machine;

FIG. 3 is a left side elevation view thereof;

FIG. 4 is a right side elevation view thereof;

FIG. 5 is front end elevation view thereof;

FIG. 6 is a rear end elevation view thereof;

FIG. 7 is a top plan view thereof; and,

FIG. 8 is a bottom plan view thereof.

The broken lines in the drawings are for illustrative purposes only and form no part of the claimed design.
